NEW YORK

PIPE STILL FURNACE

Application filed December 4, 1925. Serial No. 73,292.

This invention relates to an improved method and apparatus for controlling the fire box temperature in pipe still furnaces such as are used for heating petroleum.

When fuel is burned in a furnace the refractory walls and roof thereof absorb a good deal of heat from the burning fuel until they reach a certain temperature, depending primarily on the temperature generated by the burning of the fuel, after which they become sources of radiant heat. If the radiant heat is not absorbed and taken out of the fire box the heat then generated by the burning fuel is all converted into sensible heat carried by the products of combustion, resulting in high temperatures of these products and in the fire box.

In pipe still furnaces having the still tubes in a bank at one side of the furnace, the usual practice is to circulate the convection gas i. e., the products of combustion, downwardly through the bank on their way out of the furnace. In pipe still furnaces of this type difficulty is experienced in preventing the

upper row of tubes of the bank from becoming overheated and burning out, whereas no such difficulty is experienced with the tubes therebelow. This failure of the upper row of tubes is primarily due to two causes, namely,

the high temperature of the convection gases and the high temperature of the radiant surfaces—more particularly, the roof of the furnace. Moreover, when the bank of tubes is located at one side of a conventional bridge wall, the convection gases, in passing downwardly through the bank, tend to flow along that side of the bank remote from the bridge wall. This is due to the fact that the gases in moving upwardly from the fire-box sweep along the arched roof of the furnace and down along the wall forming the boundary at that side of the bank remote from the bridge wall. It follows, therefore, that those tubes adjacent to the bridge wall do not receive as much heat from the convection gases as do the tubes more remote therefrom.

The present invention aims to overcome in a novel manner the difficulties above indicated. Overheating of the upper row of tubes of the bank is prevented by reducing the tem-

perature of the convection gases and by shielding said tubes from highly heated radiant surfaces. The shielding means absorb heat from the burning gases and reduce fire-box temperature by absorption of heat therefrom, the net result being a reduction of the temperature of the convection gases before they reach the tubes. The firebox temperature is further controlled by injecting into the fire-box some of the convection gases after they have passed through the bank of tubes. Such gases will be relatively cool and hence will exert a cooling effect within the fire-box. The gases are returned to the fire-box independently of the fuel gases to permit complete combustion of the fuel to take place without being affected by the returned gases. The deficiency of heat supply to those tubes nearest the bridge wall is overcome by constructing the bridge wall in such a manner that it will absorb heat from the fire-box and transmit it to the adjacent tubes. The improved bridge wall is therefore also a factor in the control of fire-box temperature.

The above and other objects of the invention and features of novelty, will appear from the detailed description taken in connection with the accompanying drawings, forming part of this specification.

Referring to the drawings, Fig. 1 is a vertical section taken through the preferred form of pipe still furnace, embodying the novel features of the present invention and Fig. 2 is a horizontal section taken through the furnace, certain parts thereof being broken away to more fully show the preferred construction.

At one side of the furnace chamber is arranged a bank of tubes, generally indicated at 10, which it is desired to heat by the products of combustion i. e. the convection gases coming from the fire box at one side of said bank. The bank is arranged over a longitudinally extending conduit 12, into which the convection gases are received after having passed downwardly through the bank. The gases pass out of the conduit by way of a pair of flue passages 14, which lead from the conduit adjacent each end thereof. These flue passages 14 may come together be-

low a recuperator 16, of any suitable or preferred form, from whence the gases pass to the stack 18. The fresh air to be heated by the recuperator enters the latter at the top 5 thereof and passes downwardly between the flue passages of which the recuperator is composed. Upon reaching the bottom of the recuperator the heated air passes therefrom through a pipe 20, which leads to an air chamber 22 within the furnace construction. The fresh air is forced through the recuperator by means of a blower 24 having a suitable intake 26. The recuperator is preferably provided with a plurality of baffle plates 28 10 arranged in staggered relation, so as to cause the incoming air to travel through a circuitous path toward the bottom of the recuperator. It may sometimes be desirable to pass all or some of the gases around the recuperator. To this end there is provided a passage 30 which by-passes the recuperator. At the lower end of the by-pass 30 is a damper 31 for regulating the flow of gases around the recuperator. 15

25 Leading forwardly from the conduit 12 below the bank 10 is a passage 32 disposed centrally of the fire box and below the floor 33 thereof. This passage 32 opens onto a transversely extending passage 34, which extends 30 across the entire width of the fire box, and which is roofed over with tile members 35 having openings 36 extending therethrough. Arranged at the inlet end of the passage 32 35 is a fan 37 adapted to draw gases from the conduit 12 and force them into the fire box through the perforated tiles 35. The fan is rotated by a motor 38 located outside of the furnace proper, the motor being connected to the fan by a shaft 39 supported in suitable 40 bearings, one of which is indicated at 40 within the conduit 12. In order to prevent the bearing 40 from becoming overheated and also to keep the shaft 39 cool, there is provided a tube 42 through which the shaft 45 39 extends. This tube is open at both ends and cool air may therefore flow through it to the bearing 40. The fan is preferably rotated at a constant rate of speed.

For controlling the amount of the gases returned or injected into the fire box, suitable dampers are provided at the outlet end of the passage 32. The dampers have been shown as constituting a pair of doors 44, mounted on a common upright hinge 46. The doors 50 55 are adapted to be operated from the outside of the furnace by any suitable mechanism as by a hand lever 48 suitably mounted on the outside of the furnace and connected by a link 50 which passes through the furnace wall, said link being connected to lever 51 which in turn connects by means of a link 52 with a toggle mechanism 53 which is connected to the doors 44.

The furnace as shown is designed to be heated by a fluid fuel, preferably gas. The

fuel gases preferably enter the fire box in such a manner that they will not play directly on the bank of tubes at the side of the furnace, but will be directed away therefrom. Extending upwardly from the bottom of the 70 bank of tubes, and in front thereof, is a wall 63. In front of this wall is located a fuel gas manifold 54 in connection with a gas supply not shown. Projecting from the manifold is a plurality of gas jets 55. In 75 front of the gas jets is a perforated tile 56 through the perforations of which the gas jets discharge into the fire box. The air supply chamber 22 is located in front of the upright wall 63 and is adapted to supply the 80 necessary amount of air to the fuel gas to insure complete combustion of the fuel. The amount of air supplied to the incoming gas is controlled by a damper 57 which is adapted to be operated from the outside of the furnace in any suitable manner, as by means of a hand lever 58 to which is connected a link 59 which in turn is operatively connected to, the damper 57 by any suitable link and lever mechanism generally indicated at 60. 85

In order to permit the furnace to be fired with fuel oil, should circumstances require, there is provided a battery or row of oil burners shown as conduits 61 which have their burner ends behind the tile 56 in front 90 of openings therein, air being supplied to the oil from the air chamber 22. The oil conduits are so arranged that they may be pulled away from the tile 56 when gas is being burned so as to avoid overheating the burner end of 95 the tubes.

It will be noted that the convection gases taken from the conduit 12 are returned to the fire box remote from the point where the combustion of the fuel gases takes place. By 100 entering the convection gases at a point remote from the place of combustion of the fuel gases, the returned gases do not interfere with the rapid and complete burning of the fuel.

Instead of separating the bank of tubes from the fire box by means of a thick bridge wall, the present invention provides a bridge wall which is in effect a relatively thin curtain through which heat may be absorbed from the firebox and transmitted to the adjacent tubes. The improved bridge wall preferably takes the form of a plurality of relatively thin tiles 62 supported on the outer tubes of the bank. As shown, the tiles 110 62 are provided with curved-over upper ends 64 which hook over the outer tubes. By supporting the bridge wall in the manner indicated, there is no danger of the bridge wall collapsing under its own weight as might 115 occur if it were attempted to build the wall from the furnace floor up. Furthermore, by forming the bridge wall in the manner indicated, access may be had to the tubes by simply removing the tile members. It should 120 125 130

be noted at this point that the bank tubes run parallel with the tile members 62, or in other words, that the return bends of the tubes are at the sides of the furnace. By providing a bridge wall of the character indicated, a more uniform heating of the bank is obtained than could be obtained if the bridge wall were a thick non-conducting member. The reason for this will be seen when it is remembered that the convection gases coming from the fire box tend to flow downward through the bank along the side wall of the furnace with the result that the tubes next to and in proximity to the bridge wall do not receive as much heat as the tubes more remote from the bridge wall. As a consequence the tubes adjacent to the bridge wall would ordinarily be somewhat cooler than the tubes in closer proximity to the opposite wall of the furnace.

The heat transmitted through the thin bridge wall, therefore, supplements, as it were, the heat of the convection gases passing downwardly through the bank.

In order to shield the upper row of tubes of the bank from radiant heat from the roof of the furnace, there is arranged below the roof 65 of the furnace a series of tubes 66 which extend from wall to wall of the furnace, over the entire width of the same, said tubes preferably being in the same circuit as the tubes of the bank 10. As shown, the tubes 66 are arranged in vertically spaced rows with the tubes in one row staggered with respect to the tubes in the adjacent row as indicated in Fig. 2. The roof tubes will absorb the radiant heat from the roof and will also absorb radiant heat from the walls of the furnace. As a result of this absorption of heat the firebox temperature will be lowered and the convection gases flowing to the bank will be sufficiently reduced in temperature to prevent the upper tubes from becoming overheated.

The fluid to be heated will preferably enter the bank of tubes 10 at the bottom thereof and flow upwardly through the tubes against the down-coming convection gases and flow from the top of the bank through the roof tubes from whence they leave through a suitable conduit 68. The improved furnace has been primarily designed for the heating of petroleum oil, but is not necessarily limited to such use.

As previously indicated, the conduit 12 into which the convection gases are received after passing through the bank, is in communication near its ends with two separate flue passages 14. By providing a flue passage adjacent each end of the conduit and locating the fan 37 midway between the passages, there will be little or no tendency for the fan to draw more of the convection gases downwardly along one side or end of the bank of tubes, than at any other point of the same. Should any such tendency be indicated the flow of

the gases may be readily controlled by dampers 70 placed one in each flue passage 14. The tubes of the bank 10 may be supported between their ends in any suitable manner but preferably by spaced upright partitions as indicated at 71 through which the tubes pass. By providing upright partitions in the bank the convection gases will be obliged to flow through definite flow channels with the result that a more uniform distribution of heat may be had through the length of the bank. Partitions 72 are preferably provided adjacent each end of the bank to protect the return bends of the tubes from the heat of the furnace. The return bends of the roof tubes 66 may likewise be protected by partitions 73.

In order to prevent deterioration or failure of the still tubes due to their becoming oxidized, it is highly desirable that a non-oxidizing atmosphere be maintained within the furnace. By recirculating some of the hot products of combustion for the purpose of controlling the fire box temperature rather than by introducing an equivalent amount of air at the same temperature, I am enabled to obtain a substantially non-oxidizing atmosphere within the furnace with the result that oxidation of the still tubes is practically entirely avoided.

Aside from the fact that a substantially non-oxidizing atmosphere may be obtained in the furnace when some of the products of combustion are recirculated rather than an equivalent amount of air, there is a further increase in efficiency of the operation of the furnace by reason of the fact that no preheating of the gases is necessary. If air were to be introduced into the fire box for the purpose of controlling its temperature, it will be readily appreciated that some of the heat of the fuel—heat taken from the waste gases passing through the recuperator—would have to be given over to preheating the air.

What is claimed is:

1. In a pipe still furnace, the combination of a bank of tubes arranged at one side of the furnace fire-box, a conduit below the bank and extending lengthwise thereof, a passage leading from said conduit midway its ends, a second passage extending parallel to the conduit and in communication with the first named passage and opening into the firebox, means for introducing fuel into the fire-box in a direction away from said bank and towards the point where the second passage opens into the fire-box, means in communication with said conduit for leading products of combustion out of the furnace and means in the first named passage for causing a flow into the fire-box of some of the products of combustion which have passed through said bank.

2. A method of supplying tempered heating gases to heat absorbing means behind a wall in a furnace chamber, comprising in-

- introducing into the furnace firebox at a place remote from said wall a stream of products of combustion which have previously passed over one end of said wall and over said heat absorbing means, and directing toward said stream and from a point adjacent the opposite end of said wall, a stream of burning fuel.
3. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, and a relatively thin wall between said bank and firebox, said wall being adapted to transmit heat without a substantial drop in temperature to those tubes of said bank which are adjacent said wall.
4. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, an imperforate heat-permeable wall between said bank and firebox, said wall being adapted to transfer heat at a comparatively high rate, whereby firebox heat may pass therethrough for absorption by those tubes of said bank which are adjacent said wall, and oil heating means overlying the firebox for absorbing firebox heat.
5. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, an imperforate relatively thin wall between said bank and firebox whereby said wall being adapted to transmit heat to those tubes of said bank which are adjacent said wall at a comparatively high rate, and a bank of bare oil-heating tubes overlying the firebox for absorbing firebox heat.
6. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, a relatively thin wall between said bank and firebox, said wall being adapted to conduct heat to those tubes of said bank which are adjacent said wall without a substantial drop in temperature, and means for re-introducing into the firebox controllable amounts of combustion gases which have passed through said heating chamber whereby the heat of the firebox may be tempered.
7. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, an imperforate heat transmitting wall between said bank and firebox, said wall being adapted to transmit heat at a relatively high temperature to those tubes of said bank which are adjacent said wall, heat absorbing means overlying the firebox, and means for re-introducing into the firebox controllable amounts of combustion gases which have passed through said heating chamber whereby the heat of the firebox may be tempered.
8. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, a heat-permeable wall between said bank and firebox adapted to conduct substantial quantities of heat from said firebox to those tubes of said bank which are adjacent said wall, and means for injecting fluid fuel into the firebox in a direction away from said wall.
9. In an oil-heating furnace, the combination of a heating chamber and firebox in communication with each other at their upper ends whereby hot gases from the firebox must pass through said chamber on their way out of the furnace, a bank of oil heating tubes in said heating chamber over which said gases circulate, a heat-permeable wall between said bank and firebox whereby firebox heat may pass therethrough for absorption by those tubes of said bank which are adjacent said wall, means for injecting fluid fuel into the firebox in a direction away from said wall, and means for injecting into the firebox anterior of the injected fuel a portion of the combustion gases which have passed through said heating chamber.
10. In an oil-heating furnace, the combination of a heating chamber and firebox in communication with each other at their upper ends whereby hot gases from the firebox must pass through said chamber on their way out of the furnace, a bank of oil-heating tubes in said heating chamber over which said gases circulate, a heat-permeable wall between said bank and firebox whereby firebox heat may pass therethrough for absorption by those tubes of said bank which are adjacent said wall, means for injecting fluid fuel into the firebox in a direction away from said

wall, and means for injecting into the firebox through the floor thereof, a portion of the combustion gases which have passed through said heating chamber.

5 11. In an oil-heating furnace, the combination of a heating chamber and firebox in communication with each other at their upper ends whereby hot gases from the firebox must pass through said chamber on their way out 10 of the furnace, a bank of oil-heating tubes in said heating chamber over which said gases circulate, a heat-permeable wall between said bank and firebox whereby firebox heat may pass therethrough for absorption by those 15 tubes of said bank which are adjacent said wall, means for injecting fluid fuel into the firebox in a direction away from said wall, means for injecting into the firebox through the floor thereof, a portion of the combustion 20 gases which have passed through said heating chamber, and heat-absorbing means overlying the firebox.

12. In a furnace, the combination of a heating chamber and a firebox in communication 25 with each other at their upper ends whereby hot gases from the firebox must pass through the heating chamber on their way out of the furnace, means for introducing into the firebox at a point remote from the division wall 30 between the firebox and heating chamber a portion of the hot gases which have passed through said heating chamber, and means for introducing burning fuel into the firebox in a direction away from said division 35 wall and toward the place of reintroduction of said gases into the firebox.

13. In a furnace, the combination of a heating chamber and a firebox in communication with each other at their upper ends whereby 40 hot gases from the firebox must pass through the heating chamber on their way out of the furnace, means for introducing burning fuel into the firebox toward that wall of the firebox which is opposite the division wall between 45 the firebox and heating chamber, means for introducing into the firebox at a place between said walls a controlled amount of the hot gases which have passed through said heating chamber, and a series of bare tubes in 50 the roof of the firebox through which a fluid to be heated may be passed, said tubes adapted to absorb radiant heat from the firebox.

14. In a furnace, the combination of a heating-chamber and a firebox in communication 55 with each other at their upper ends whereby hot gases from the firebox must pass through the heating chamber on their way out of the furnace, means for introducing burning fuel into the firebox toward that wall of the firebox which is opposite the division wall between 60 the firebox and heating chamber, means for introducing into the firebox at a place between said walls a controlled amount of the hot gases which have passed through 65 said heating chamber, a series of bare tubes

in the roof of the firebox through which a fluid to be heated may be passed, said tubes adapted to absorb radiant heat from the firebox, and a bank of tubes in said heating chamber through which a fluid to be heated 70 may be passed.

15. In a furnace structure, the combination of a fire-box and a heating chamber communicating with each other over a bridge wall, 75 said wall being adapted to transfer heat from said fire-box to said chamber at a comparatively high rate, a heat absorbing element in said chamber, means for jetting burning fuel into said fire-box in a direction away from said wall, and a cooling screen comprising a bank of tubes above said fire-box adapted to absorb heat radiated from said fire-box, said bank of tubes being substantially entirely out of the path of flow of the combustion 80 gases.

16. The method of controlling the intensity of heat applied by products of combustion to the tube bank of a furnace in which said bank is separated from the fire-chamber of said furnace by a bridge wall over which said products of combustion pass, and in which a bare tube screen is provided under the roof of said furnace above said bridge wall and substantially entirely out of the path of flow of the products of combustion, which comprises passing a heat-absorbing fluid through the tubes of said screen to absorb radiant heat from said fire-chamber and thereby prevent substantial radiation of heat to said bank, and tempering the products of combustion in said fire chamber by mixing therewith the products of combustion which have been cooled by passage over said bank 90 of tubes.

17. In an oil heating furnace, which comprises a fire-box, a heating chamber and a heat-absorbing tube bank, in said chamber, the improvement which comprises a relatively thin imperforate bridge wall separating said fire-box and heating chamber and over which hot products of combustion produced in said fire-box pass into said chamber, said wall being adapted to transmit substantial quantities of heat from said fire-box to the tube bank in said chamber, and means for jetting fuel into said fire-box in a direction away from said wall, thereby to direct the hot gases of combustion away from said wall.

18. In an oil heating furnace, which comprises a combustion chamber, a heating chamber and a bank of oil conducting tubes in said heating chamber, and in which hot gases of combustion from said combustion chamber are passed over the tubes in the heating chamber, the improvement which comprises a relatively thin imperforate bridge wall separating said chambers and around which the products of combustion pass from said combustion chamber to said heating chamber, said

ing chamber, a first tube group comprising a plurality of fluid-conveying tubes in the heat absorption chamber, a second tube group comprising a plurality of rows of vertically spaced exposed fluid-conveying tubes under the entire roof and arranged above the top of the bridge wall and spaced from said top of the bridge wall and above the tubes of the first group, said tubes of the first group being arranged to be heated by convection heat, and said second tube group being arranged to be heated by radiant heat and means to conduct fluid from the first tube group to the second tube group, the arrangement being such that the uppermost tubes of the second group are in a zone of relatively still gas.

25. An oil-heating furnace comprising walls forming a setting, means for effecting combustion of fuel to provide a source of radiant heat in said setting, a first tube group in said setting exposed to direct radiant heat from said source, a second tube group in said setting, and a wall of thin imperforate tile in said setting between said second tube group and said source, said wall providing communicating chambers in said setting, the source of heat being in one chamber and said second tube group being in a second chamber, and said wall serving to transmit heat through the material thereof from said source to said second tube group.

26. An oil-heating furnace comprising walls forming a setting, means for effecting combustion of fuel to provide a source of radiant heat in said setting, a first tube group in said setting exposed to direct radiant heat from said source, a second tube group in said setting, and a continuous wall of thin material in said setting between said second tube group and said source, said wall providing communicating chambers in said setting, the source of heat being in one chamber and said second tube group being in a second chamber, and said wall serving to transmit heat through the material thereof from said source to said second tube group.

27. An oil-heating furnace comprising walls forming a setting, means for effecting combustion of fuel to provide a source of radiant heat in said setting, a first tube group in said setting exposed to direct radiant heat from said source, a second tube group in said setting, a wall of thin imperforate tile in said setting between said second tube group and said source, said wall providing communicating chambers in said setting, the source of heat being in one chamber and said second tube group being in a second chamber, said wall serving to transmit heat through the material thereof from said source to said second tube group, and means to remove products of combustion from said second chamber.

28. An oil-heating furnace comprising walls forming a setting, means for effecting

combustion of fuel to provide a source of radiant heat in said setting, a first tube group in said setting exposed to direct radiant heat from said source, a second tube group in said setting, a continuous wall of thin material in said setting between said second tube group and said source, said wall providing communicating chambers in said setting, the source of heat being in one chamber and said second tube group being in a second chamber, said wall serving to transmit heat through the material thereof from said source to said second tube group, and means to remove products of combustion from said second chamber.

29. In an oil-heating furnace, wall structure forming a heating chamber and a firebox in communication with each other whereby hot gases from the firebox pass into said chamber on their way out of the furnace, a tube group exposed to direct radiant heat from the hot gases in the firebox and substantially entirely out of the path of flow of said gases, and a bank of oil-heating tubes in said heating chamber over which said gases circulate, said wall structure including a relatively thin imperforate wall between said bank and said firebox, and said wall being adapted to transmit a substantial amount of heat through the material thereof to those tubes of said bank in the heating chamber which are adjacent said wall.

30. An oil still furnace comprising side walls and a roof, a bridge wall extending upwardly, terminating short of the roof and dividing said oil still furnace into a heating chamber and a heat absorption chamber, means for effecting combustion of fuel to develop relatively intense radiant heat in the heating chamber, a first tube group comprising a plurality of superposed rows of fluid conveying tubes in the heat absorption chamber and a second tube group comprising a plurality of vertically spaced rows of bare fluid conveying tubes under and adjacent the roof and exposed to direct radiant heat produced in the heating chamber, said plurality of rows of the second tube group comprising an upper row immediately adjacent the roof and a lower row immediately under said upper row, the tubes of the lower row and higher row being staggered with respect to each other, said lower row being at a higher elevation than the top of the bridge wall and at a higher elevation than the uppermost row of tubes in said heat absorption chamber whereby a substantial amount of heating gases may pass over the bridge wall and into the heat absorption chamber without giving up heat of convection to the second tube group, said second tube group being disposed under substantially the entire roof portion above the heating chamber.

31. An oil still furnace comprising an enclosure defined by walls arranged substantially

tially right angles to each other, a thin imperforate bridge wall extending substantially at right angles from one of said enclosing walls and terminating short of the wall
5 opposite said last mentioned wall, said bridge wall dividing the oil still furnace into a heating chamber and a heat absorption chamber communicating with each other, means for effecting combustion of fuel to
10 develop relatively intense radiant heat in the heating chamber, a first tube group comprising a plurality of rows of fluid conveying tubes in the heat absorption chamber, and a second tube group comprising a plurality of
15 spaced, bare fluid conveying tubes disposed adjacent to and extending entirely across the wall opposite said last mentioned wall, said second tube group being spaced from the outer end of the bridge wall whereby direct
20 flow of heating gases may be established over the outer edge of the bridge wall and into the heat absorption chamber without said heating gases giving up a substantial amount of heat of convection to the second tube
25 group, said bridge wall being adapted to transmit heat through the material thereof from the heating chamber to those tubes of the first tube group which are adjacent the bridge wall, and means to remove products
30 of combustion from said heat absorption chamber.

In testimony whereof I affix my signature.
DAVID G. BRANDT.
